CLAIM

The ornamental design for a butterfly knife as shown and described.

DESCRIPTION

FIG. 1 is a top, front, right perspective view of a butterfly knife, showing my new design in its opened position;

FIG. 2 is a top, rear, left perspective view of the butterfly knife shown in FIG. 1;

FIG. 3 is a right elevation view of the butterfly knife shown in FIG. 1;

FIG. 4 is a left elevation view of the butterfly knife shown in FIG. 1;

FIG. 5 is a top plan view of the butterfly knife shown in FIG. 1;

FIG. 6 is a bottom plan view of the butterfly knife shown in FIG. 1;

FIG. 7 is a front elevation view of the butterfly knife shown in FIG. 1;

FIG. 8 is a rear elevation view of the butterfly knife shown in FIG. 1.

FIG. 9 is a top, front, right perspective view of a butterfly knife, showing my new design in its closed position;

FIG. 10 is a top, rear, left perspective view of the butterfly knife shown in FIG. 9;

FIG. 11 is a right elevation view of the butterfly knife shown in FIG. 9;

FIG. 12 is a left elevation view of the butterfly knife shown in FIG. 9;

FIG. 13 is a top plan view of the butterfly knife shown in FIG. 9;

FIG. 14 is a bottom plan view of the butterfly knife shown in FIG. 9;

FIG. 15 is a front elevation view of the butterfly knife shown in FIG. 9; and,

FIG. 16 is a rear elevation view of the butterfly knife shown in FIG. 9.
